W. P. KONDRAT.

SASH LOCK.

APPLICATION FILED JULY 14, 1919.

1,360,413.

Patented Nov. 30, 1920.

UNITED STATES PATENT OFFICE.

WLADYSLAW P. KONDRAT, OF CLEVELAND, OHIO.

SASH-LOCK.

1,360,413.

Specification of Letters Patent. Patented Nov. 30, 1920.

Application filed July 14, 1919. Serial No. 310,538.

To all whom it may concern:

Be it known that I, WLADYSLAW P. KONDRAT, a citizen of the United States, residing at Cleveland, in the county of Cuyahoga and State of Ohio, have invented certain new and useful Improvements in Sash-locks, of which the following is a specification, reference being had to the accompanying drawings.

10 This invention relates to an improved sash lock, and an object of the invention is to provide a sash lock capable of locking both sashes in open positions.

One of the objects of the invention is to 15 provide a sash locking device for so locking the upper and lower sashes as to permit one or the other to open a short distance, sufficient to permit of proper ventilation, and yet will not allow the passage of a body 20 through the window into the room.

A further object of the invention is the 25 provision of means carried by the locking member proper, to frictionally engage a housing for said member, to hold the locking end of the member from under an opening in an element which receives the end of the locking member, so that the two sashes may be opened their full distance.

While the design and construction at 30 present illustrated and set forth is deemed preferable, it is obvious that as a result of a reduction of the invention to a more practical form for commercial purposes, the invention may be susceptible to changes, and 35 the right to these changes is claimed, provided they are comprehended within the scope of what is claimed.

The invention comprises further features 40 and combination of parts, as will be herein-after set forth, shown in the drawings and claimed.

In the drawings:

Figure 1 is a perspective view of a portion 45 of the side of the window frame, showing the upper and lower sashes and the sash locking mechanism applied thereto.

Fig. 2 is a vertical sectional view on line 2—2 of Fig. 1.

Fig. 3 is a plan sectional view on line 3—3 50 of Fig. 2, showing parts broken away.

Fig. 4 is a detail perspective view of the holding guide plate which is secured upon the upper rail of the lower sash, and in which the locking member is mounted and 55 guided.

Fig. 5 is a detail perspective view of the locking member.

Referring more especially to the drawings, 1 designates a portion of the side of a window frame, and 2 and 3 denote the upper and lower sashes of the window. Secured by any suitable means preferably screws 4, to one of the side rails of the upper sash is an elongated plate 5. This plate has an elongated portion 6, which is concavo-convex in cross-section, due to the fact that said portion 6 is pressed outwardly of the plate. This outwardly pressed elongated portion is provided with an elongated slot 7. The upper end of the outwardly 60 pressed portion 6 is closed as shown at 8, while the lower portion thereof terminates a short distance above the lower part of the plate. In fact, the lower part of the outwardly pressed portion 6 is cut away, to provide an opening 9. 65

The lower end of the plate 5 is provided with a laterally extending flange 10, which extends at right angles to the body of the plate, and is arranged to cover the upper end 80 of a groove 11, which is formed in the rear face to one side of the upper rail 12 of the lower sash. This groove or opening 11 is constructed for the purpose of permitting the outwardly pressed portion 6 of the plate 5 85 to pass the upper rail 12 of the lower sash, when the upper sash is lowered, or when the lower sash is raised. The object of covering the groove or opening 11 is to prevent an instrument of any kind from being inserted through the groove, for the purpose of actuating the locking member of the sash lock. 90

A holding guide casing 13 is mounted upon the upper rail 12 of the lower sash. 95 This casing 13 is open at one end as shown and closed at 14 at its opposite end. By means of screws 15 passing through the flanges 16, the casing 13 is secured to the upper rail of the lower sash. The upper 100 wall of the casing 13 is provided with an elongated slot. Mounted in the casing 13 is the body 19 of the locking member. The body of the locking member is elongated and rectangular in form, conforming to the 105 contour of the casing, so as to be guided therein, during its movements toward and from the plate 5. One end of the body of the locking member tapers as shown at 20, and the tapered extremity terminates in a 110

reduced neck 21, which is of a thickness to neatly fit the elongated slot 7 of the plate 5, that is when the lower sash is raised, or the upper sash lowered. Formed integral with 5 the neck 21 is a head 22, which is substantially of a width corresponding to the width of the body 19 of the locking member. One face of the head is flat as shown at 23, while the opposite face bevels off from 10 a point adjacent the neck 21, to the marginal edge of the head. The portion 24 of the bevel of the head constitutes means to guide and cam the head under the walls of the outwardly pressed portion 6 of the plate 5, that is when the neck 21 enters the slot 7, when the upper sash is lowered or the lower sash raised. The side portions 25 of the bevel of the head are of such shape, as to conform to the 15 curvature of the outwardly pressed portion 6 of the plate, so as to insure a firm connection between the head and the plate, when the head is in engagement therewith.

The upper wall of the casing 13 at a point 25 adjacent the plate 5 is cut away as shown at 26, to permit the locking member to be moved in a direction from the plate 5, so as to conform to and receive the beveled face of the head, and also to permit the head to be positioned from under the lower open 30 end of the slot 7, of which the upper end 27 is closed. When the locking member is moved in order to position the head from under the lower open end of the slot, it is possible to raise the lower sash, or lower the 35 upper sash, without locking the two sashes together for limited movement. The end portions of the flanges 16 nearest the adjacent faces of the meeting rails of both 40 sashes are provided with extension lugs 28, which are embedded or countersunk in one face of the rail 12, and secured by screws 29, thereby additionally securing the casing 13 in position.

45 A thumb piece 30 has an extension 31, which is of a reduced diameter sufficient to enter the slot 17 of the upper wall of the casing 13, whereby the thumb piece 30 may engage the upper surface of the top wall of 50 the casing. A second reduced extension 32 projects from the extension 31 and is secured into the body 19 of the locking member in any suitable manner, say for instance, by friction or by shrinking the same 55 in place, so that the shoulder 33 intermediate the two extensions will engage in the upper face of the body of the locking member. A leaf spring 34 extends through the slot 17 and has one end mounted upon the 60 reduced extension 31, at a point between the upper wall of the casing 13, and the upper surface of the body of the locking member, hence holding the leaf spring in position.

The leaf spring 34 is bent at 35 to extend vertically downwardly, thereby pro-

viding a shoulder 18, which engages one of the end edges of the slot 17, thereby holding the locking member so that the head will be positioned under the channel of the plate 5. By means of this shoulder 18 engaging one 70 of the end edges of the slot, the locking member is prevented from accidental displacement, in such wise as to move the head of the locking member from under the channel of the plate 5. The lower part of the 75 vertical part of the leaf spring is again bent as at 37 to form the tongue 36, which tongue engages under the upper wall of the casing 13, particularly when the bent portion 35 and the inclined part of the spring 80 34 is protruding through the slot 17. In other words, the tongue 36 limits the movement of the leaf spring through the slot. When it is desired to remove the head of the locking member from under the lower end 85 of the channel of the plate 5, the spring 34 may be depressed, so that the bent part 35 is in a position to ride under the top wall of the casing 13, that is when the locking member is moved laterally of the lower sash, by 90 grasping the headed pin 39. When the spring 34 is depressed, the vertical portion of the leaf spring and the tongue will enter the opening 38 in the body 19 of the locking member. When the locking member is 95 moved, so as to withdraw the head from under the channel, the bent portion 35 of the leaf spring will ride against the under surface of the top wall of the casing 13, and frictionally engage therewith, in order to 100 hold the locking member with its head from under the lower end of the channel of the plate 5. A headed pin 39 is guided in an opening in the closed end wall of the casing 13, and is threaded at 40 in the one end of 105 the body 19 of the locking member. By means of this headed pin, the locking member is guided and reinforced, during the movement of the locking member, when the locking member is manipulated toward and 110 from the plate 5. In order to lock the sashes, for limited movements, the locking member is arranged, as shown clearly in Figs. 1 and 2, hence when the lower sash is raised, the head of the locking member will 115 enter the space between the plate 6 and the inner face of one of the side rails of the upper sash, particularly since the head conforms to the inner face of the outwardly pressed portion 6 of the plate 5. Should 120 an attempt be made to raise the lower sash or lower the upper sash, the upper closed end 27 of the slot 7 will contact with the neck 21 of the locking member, and hence limit either one of the sashes in its movement. In order that the neck may contact with the closed end 27 of the slot, the head of the locking member enters the outwardly pressed portion of the plate 5, whereas the neck 21 enters the slot 7. In order to raise 125 130

the lower sash to its fullest extent or likewise lower the upper sash, the thumb piece 30 may be grasped, and the locking member moved to a direction from the plate 5, 5 thereby disposing the neck from under the lower open end of the slot 7, and also to move the head from under the channel or space between the outwardly pressed portion 6 of the plate 5 and the face of the side 10 rail of the upper sash.

When the locking member is moved so as to dispose the nut and the head from under the lower end of the slot and channel of the plate 5 and held in such a position by the 15 bent portion 35 frictionally engaging the under surface of the top wall of the casing 13, it will be seen that either one of the sashes may be moved its fullest extent.

The invention having been set forth, what 20 is claimed as new and useful is:—

The combination with upper and lower sashes, of an elongated plate carried by the upper sash and provided with an elongated channel, of a holding and guiding casing 25 secured in a transverse position on the upper rail of the lower sash, a sash locking member mounted in said casing and having a head adapted to enter the channel of said plate, to permit the sashes to open partially 30 relatively to each other, the upper wall of

said casing having a slot, a headed element projecting through the slot and carried by the locking member, a leaf spring mounted on the headed element between its head and the body of the locking member, said leaf 35 spring having a bent portion adapted to project through the slot, said bent portion having a shoulder to engage one end edge of the slot, to hold the head of the locking member under, and in a position to engage 40 said channel, the locking member having an opening to receive the bent portion, when the leaf spring is depressed, whereby the leaf spring adjacent the bent portion may frictionally contact with the under surface 45 of the top wall of the casing to hold the head of the locking member from under the channel, and a device carried by the locking member and guided in the end wall of the casing, to retract the locking member 50 when the leaf spring is depressed and the bent portion in engagement with said opening.

In testimony whereof I hereunto affix my signature in the presence of two witnesses. 55
